STEER ROPING TRAINER OR THE LIKE

Robert L. Kelton, 1895 Hayden Lane,
Tempe, Ariz. 85281

Filed Aug. 13, 1973, Ser. No. 388,324

Term of patent 14 years

Int. Cl. D19—07

U.S. Cl. D19—59

FIG. 1 is a perspective view of one side and end of a steer roping trainer or the like;

FIG. 2 is a perspective view of the other side and end of the steer roping trainer or the like shown in Fig. 1; and

FIG. 3 is a side view of the structure shown in FIG. 1.
I claim:

The ornamental design for a steer roping trainer or the like, as shown and described.
